(57) **CLAIM**

The ornamental design for a shoe protector mat with no-skid backing, as shown and described.

DESCRIPTION

FIG. 1 is a top plan view of a shoe protector mat with no-skid backing, showing my new design;

FIG. 2 is a bottom plan view thereof;

FIG. 3 is a right side view thereof, it being understood that the left side is a mirror image thereof; and,

FIG. 4 is a front elevation view thereof, it being understood that the rear elevation view is a mirror image thereof.

1 Claim, 2 Drawing Sheets

FIG. 1

FIG. 2

FIG. 3

FIG. 4
